ATTORNEY

UNITED STATES PATENT OFFICE.

ROBERT E. THOMAS, OF HUGO, OKLAHOMA.

PEANUT-HARVESTER.

1,263,149.

Specification of Letters Patent. Patented Apr. 16, 1918.

Application filed September 12, 1917. Serial No. 190,998.

To all whom it may concern:

Be it known that I, ROBERT E. THOMAS, a citizen of the United States, residing at Hugo, in the county of Choctaw and State 5 of Oklahoma, have invented new and useful Improvements in Peanut-Harvesters, of which the following is a specification.

This invention relates to peanut harvesters and it has for its object to produce a 10 machine of this class which will possess superior advantages in point of simplicity, durability and general efficiency.

With these and other ends in view which will readily appear as the nature of the invention is better understood, the same consists in the improved construction, novel arrangement and combination of parts which will be hereinafter more fully described and pointed out in the claims.

20 In the accompanying drawing has been illustrated a simple and preferred form of the invention, it being, however, understood that no limitation is necessarily made to the precise structural details therein exhibited, 25 but that changes, alterations and modifications within the scope of the claims may be resorted to when desired.

In the drawing:—

Figure 1 is a perspective view of a device 30 constructed in accordance with the invention.

Fig. 2 is a top plan view.

Fig. 3 is a transverse sectional view taken on the line 3—3 in Fig. 2.

35 Fig. 4 is a sectional detail view taken on the line 4—4 in Fig. 3.

Corresponding parts in the several figures are denoted by like characters of reference.

Referring to the drawing, 15 designates a 40 ring or hoop which may be made of bar steel of any suitable dimensions, it being found that material two inches wide and three-eighths of an inch in thickness is suitable for the purpose. The hoop 15 which 45 may be of any desired diameter is preferably formed by bending the bar from which it is formed and overlapping the ends of said bar, the overlapped ends being secured by means of bolts 16 on the top face of a beam 50 17 near the rearward end of the latter, the ends of the bar might be welded together but this is not considered necessary by the construction shown and described.

Secured on the inner face of the hoop 55 15 in the bottom portion thereof is a digger blade 18 made of sheet steel, said blade be-

ing of substantially triangular form although the side edges thereof are preferably rounded in a forward direction where they terminate in the point 19. The blade is 60 curved to conform to the curvature of a hoop on which it may be bolted, riveted or otherwise firmly secured.

The sides of the hoop 15 are connected with the beam by forwardly extending 65 braces 20. Handles 21 are also connected with the sides of the beam slightly in advance of the hoop 15, said handles extending forwardly and rearwardly. The handles are reinforced by means of a U-shaped 70 brace 22 the limbs of which are bolted or secured on the inner faces of the handles, the bridge portion of said brace being connected with the hoop and with the beam by means of the bolts 16, the latter serving to assemble 75 together the beam, the hoop and the U-shaped brace, and also to connect together the overlapped ends of the bar from which the hoop is formed. The handles will thus be strongly reinforced and the parts of the 80 device will be assembled together in a very effective and durable manner. A draft clevis 23 may be seen at the front end of the beam.

That portion of the hoop which extends 85 beneath the digger blade and which extends upwardly adjacent to the sides thereof below the braces 20 is preferably beveled to produce a sharp cutting edge thereby avoiding any obstructions to the progress of the 90 machine when in operation.

For the purpose of gathering the vines in advance of the machine and guiding the same into the hoop 15, gathering members or hooks 24 are provided, the same being 95 connected with the beam 17 and well in advance of the annular hoop, and the said hooks being so shaped as to gather the vines and prevent choking of the device as it advances. It is also desirable to provide a rudder plate 25 extending rearwardly with respect to the hoop 15, said rudder plate being arranged to extend rearwardly with respect to the digger 15 about midway between the sides of the latter so as to travel in the 100 furrow made by the device, thereby tending to prevent the device from swaying or wobbling sidewise.

From the foregoing description, taken in connection with the drawing hereto annexed 110 the operation and advantages of this invention will be readily understood. The device

is guided along the row of vines, the digger penetrating into the ground and severing the roots, the vines passing unobstructedly through the hoops behind which they are left on the ground in a convenient position to be subsequently gathered by means of a pitch fork. Peanuts and the like may in this manner be easily and inexpensively harvested without loss and without necessity for stooping in gathering the vines in the manner now usually practised.

What is claimed, is:—

1. A device of the class described comprising a beam, a hoop having overlapped ends above said beam, upwardly and rearwardly extending handles secured to the sides of the beam in advance of the hoop, a U-shaped brace, the limbs of which are secured to the inner faces of the handles, bolts assembling the bridge portion of the U-shaped brace with the beam and with the overlapped ends of the hoop, and a digger

blade carried by the hoop, said blade being curved to conform to the curvature of the hoop.

2. A device of the class described comprising a beam, a hoop having overlapped ends above said beam, upwardly and rearwardly extending handles secured to the sides of the beam in advance of the hoop, a U-shaped brace, the limbs of which are secured to the inner faces of the handles, bolts assembling the bridge portion of the U-shaped brace with the beam and with the overlapped ends of the hoop, and a digger blade carried by the hoop, said blade being curved to conform to the curvature of the hoop, the portion of the hoop lying beneath the digger and extending upwardly adjacent to the sides thereof being beveled to produce sharp cutting edges.

In testimony whereof I affix my signature.

ROBERT E. THOMAS.
